WIRE SPLICER

Laudie E. Krosman, Scio, Oreg.

Application September 1, 1933, Serial No. 687,906

9 Claims. (Cl. 140—118)

This invention relates generally to wire-working tools, and particularly to a tool for splicing together the ends of a pair of wires, and is a continuation in part of my co-pending application, Serial No. 660,918, filed March 15, 1933 and entitled Wire splicer.

My said application Serial No. 660,918 provides means for admirably connecting the ends of a pair of wires by splicing, but the splice made thereby leaves straight portions of wire between the terminal coils of the splice.

It is an object of the present invention to provide means for making a splice in such a way that the straight wire portions between the terminal coils will also be coiled or twisted, so as to provide a neater, stronger, splice, more uniform in cross section.

Other objects and advantages of the present invention will be apparent from a reading of the following description in connection with the drawing, wherein for purposes of illustration I have shown a preferred embodiment.

In the drawing:—

Figure 1 is a general perspective view of said embodiment.

Figure 2 is a side elevational view.

Figure 3 is a top plan view showing a pair of wires in place for producing the twist of the wire portions intermediate the terminal coils.

Figure 4 is a view similar to Figure 3 showing the application of the pliers (shown in dotted line) to the twisted intermediate portion while forming of the terminal coils.

Figure 5 is a top plan view of a portion of the main body of the embodiment with the closure plate removed.

Figure 6 is a side elevational view of a splice produced by the said embodiment.

Referring in detail to the drawing, the numeral 5 refers generally to an elongated rectangular block which has in its top surface parallel to and adjacent to one longitudinal side thereof a rounded relatively deep groove 6 which extends from one end of the block to a point approximately the middle thereof where it opens into a relatively large half-moon opening 7. Traversing the block at oppositely right angles to the groove 6 and opening into the recess 7 and through the opposite side of the block is another relatively deep rounded groove 8. Similarly opening into the recess 7 next to the groove 8 is a third groove 8a, whose outward end opens through the opposite side of the block. It will be noted that the groove 8a is absent in the device which is the subject matter of my co-

pending application Serial No. 660,918. This groove 8a enables the improvement in splicing referred to herein.

On the side of the block 5 opposite the half-moon recess 7 and having its apex traversed by the groove 8 is the triangular main body portion 9. This provides for adequate length of the groove 8 without unnecessarily widening the block 5. It will be noted that the groove 8a opens through the side of the block at the point where one side of the triangular projection 9 meets the longitudinal side of the block 5.

Mounted at the side of the groove 8 opposite the location of the groove 8a and pivoted to the upper surface of the block by means of the screw 12 is the swingable closure plate generally designated 13 which is formed of relatively thin metal in such shape and form as to coincide with the shape of the top portion of the block 5 which it covers when in the closed position illustrated in Figures 3 and 4. One side of the closure 13 has a large clearance notch 19 which provides access to the recess 7 when the plate is closed. The triangular portion of the closure plate 13 which overlies the triangular projection 9 is designated 14, while a cut away portion 15 defines the handle 16. A second and smaller sight notch 18 is located outwardly of the relative large notch 19.

In utilizing the embodiment of the present invention one of the wire ends 20 is located in the groove 8a and the other wire end 21 in the groove 8. A pliers generally designated 22 is used to hold the wires in side by side relationship and the body 5 is rotated to twist the wires as indicated at 21a to produce the intermediate twisted portion of the splice joint herein mentioned. After this has been completed, the wire 20 is bent laterally and disposed in the groove 6. The change of position from that shown in Figure 3 to that shown in Figure 4 is thus accomplished. The pliers 22 is then transferred from the straight portions of the wire lying outward of the twisted portion 21a, to the portion 21a and the main body 9 rotated to produce the first of the terminal coils 25. When this terminal coil 25 has been produced, the wire ends 20, 21 are taken out of the device and the wire ends remaining placed in the positions shown in Figure 4, with the pliers grasping the intermediate portion 21a, and the body 5 rotated to produce the second terminal coil 26, upon the completion of which the splice joint is finished, and has the form illustrated in Figure 6. It will be observed that the formation of one of the terminal coils 116

tends to tighten the intermediate portion 21a. Although I have shown and described herein a preferred embodiment of my invention, it is to be definitely understood that I do not desire 5 to limit the application of the invention thereto, and any change or changes may be made in material and structure and arrangement of parts, within the spirit of the invention and the scope of the subjoined claims.

10. What is claimed is:-

1. In a wire working tool for splicing a pair of wire ends, a block having a longitudinal groove and a pair of transverse grooves in one side thereof, one end of each of said grooves opening 15 into a common recess, a closure plate movably connected to the same side of the block for positioning over said grooves to hold the wire ends therein.

2. In a wire working tool for splicing a pair of wire ends, a block having a longitudinally arranged groove and a pair of transverse grooves in one side thereof, said side and a portion of one longitudinal edge of said block being formed with a recess into which one end of each of said 25 grooves opens, a closure plate movably connected to said one side and arranged to close said grooves for holding the wire ends therein.

3. In a wire working tool for splicing a pair of wire ends, a block having a longitudinally arranged groove and a pair of transverse grooves in one side thereof, said side and a portion of one longitudinal edge of said block being formed with a recess into which one end of each of said 30 grooves opens, a closure plate movably connected to said one side and arranged to close said grooves for holding the wire ends therein, one of said transverse grooves being arranged at an acute angle to the remaining transverse groove.

4. In a wire working tool for splicing a pair of wire ends, a block having a longitudinally arranged groove and a pair of transverse grooves in one side thereof, said side and a portion of one longitudinal edge of said block being formed 45 with a recess into which one end of each of said grooves opens, a closure plate movably connected to said one side and arranged to close said grooves for holding the wire ends therein, one of said transverse grooves being arranged at 50 right angles to said longitudinal groove.

5. In a wire working tool for splicing a pair of wire ends, a block having a longitudinally arranged groove and a pair of transverse grooves

in one side thereof, said side and a portion of one longitudinal edge of said block being formed with a recess into which one end of each of said grooves opens, a closure plate movably connected to said one side and arranged to close said grooves for holding the wire ends therein, said recess being arranged at approximately the middle of said block.

6. In a wire working tool for splicing a pair of wire ends, a block having a longitudinally arranged groove and a pair of transverse grooves in one side thereof, said side and a portion of one longitudinal edge of said block being formed with a recess into which one end of each of said 80 grooves opens, a closure plate movably connected to said one side and arranged to close said grooves for holding the wire ends therein, said grooves terminating at said recess.

7. In a wire working tool for splicing a pair of wire ends, a block having a longitudinally arranged groove and a pair of transverse grooves in one side thereof, said side and a portion of one longitudinal edge of said block being formed with a recess into which one end of each of said 85 grooves opens, a closure plate movably connected to said one side and arranged to close said grooves for holding the wire ends therein, said grooves terminating at said recess.

8. In a wire working tool for splicing a pair

of wire ends, a block having a longitudinally arranged groove and a pair of transverse grooves in one side thereof, said side and a portion of one longitudinal edge of said block being formed with a recess into which one end of each of said 90 grooves opens, a closure plate movably connected to said one side and arranged to close said grooves for holding the wire ends therein, said longitudinal groove being located close to said 95 edge of the block.

9. In a wire working tool for splicing a pair

of wire ends, a block having a longitudinally arranged groove and a pair of transverse grooves in one side thereof, said side and a portion of one longitudinal edge of said block being formed with a recess into which one end of each of said 100 grooves opens, a closure plate movably connected to said one side and arranged to close said grooves for holding the wire ends therein, said closure plate having an opening exposing said 105 recess while said closure plate is closed.

10. In a wire working tool for splicing a pair

of wire ends, a block having a longitudinally

arranged groove and a pair of transverse grooves

in one side thereof, said side and a portion of

one longitudinal edge of said block being formed

with a recess into which one end of each of

said grooves opens, a closure plate movably

connected to said one side and arranged to close

said grooves for holding the wire ends therein,

said closure plate being pivoted to said one side

110 of the block at one side of said transverse

grooves.
